UNITED STATES PATENT OFFICE

ALFRED FALLOT, DECEASED, LATE OF PLAUE, GERMANY; BY HARRY PRIESTER, EXECUTOR, OF BERLIN, GERMANY

TWO-COLOR ROTARY PRINTING MACHINE

Original application filed February 1, 1924, Serial No. 690,030, and in Germany February 14, 1923. Divided and this application filed May 2, 1928. Serial No. 274,597.

This invention relates to a rotary printing machine for printing in two different colors. The known machines of this type have a comparatively large number of cylinders and, in consequence, are either very high or require a large floor space. One particular type is known having two inking mechanisms in connection with one plate cylinder, with the result, that changing the inking rollers is difficult, and that only one damping device can be arranged for these two inking mechanisms in common. This, however, has proved to be a great handicap in practical work since it makes it impossible to independently regulate the water supply for the plate cylinders.

The arrangement of the plate cylinders, in both these cases, is not very serviceable and the various parts of the machine are not as supervisible and accessible as would be required in offset printing machines, to which this invention has special reference. This type of machine is designed to perform very delicate work and requires just as delicate attention. There exists another drawback in connection with machines having a separate plate cylinder for each color, which consists in that the printing pressure of the two plate cylinders upon the blanket cylinder starts at different times, so that the prints frequently have a smudged or striped appearance when finished.

All these disadvantages are overcome by the arrangement according to the invention which essentially consists in the provision of a blanket cylinder, two plate cylinders of the same diameter as the blanket cylinder, and an impression cylinder of only half that diameter. The sheet coming from a feeding device, for instance from a feed table or from feed rolls, is seized by the grippers of the small cylinder and carried once around same, during which time it is printed upon with one color by one of the two printing surfaces of the blanket cylinder, whereupon it is seized by grippers on the second printing surface of the blanket cylinder and, while passing the small impression roller, receives its second color design. The sheet

then moves to the delivery device past the plate cylinder for the first color.

According to the invention the arrangement is such, that the axes of the blanket cylinder and of the two plate cylinders are all positioned in one plane, and the offset surfaces of the plate cylinders are disposed so that the printing pressure upon the blanket cylinder of both plate cylinders commences simultaneously. Owing to this arrangement the pressures exerted by the two plate cylinders upon the blanket cylinder counter-act each other, so that clear printing may be relied upon.

In the drawing one embodiment of the invention is illustrated, the figure showing diagrammatically a part sectional side elevation of the machine.

In the example shown in this drawing, the paper is fed into the machine from a feed table *a*. It is seized by the grippers *b* of the small impression cylinder *c* and moved once around this cylinder, during which movement the sheet is printed upon with one color by the blanket *d* of the blanket cylinder *e*, which latter has received the design from the zinc plate *f* of the plate cylinder *g*. After having completed one revolution on the small impression cylinder *c* the sheet is seized by the grippers *h* which are provided near the starting edge of the second printing surface *i* of the blanket cylinder *e*, and deposited onto this surface with that side which has already once been printed upon during the aforesaid stage. This printing surface *i* receives its design from the zinc plate *k* of the second plate cylinder *l*. During its passage between the impression cylinder *c* and the blanket cylinder *e* the sheet is printed upon with the second color, whereupon it passes between the blanket cylinder and the set-off portion *m* of cylinder *g* to be transferred to the delivery cylinder *n*. Portion *o* of the plate cylinder *l* is not covered by the zinc plate *k* and is likewise set-off, so as not to contact with rubber blanket *d* of the blanket cylinder *e* during its passage.

The plate cylinders *g* and *l* are each provided with a damping mechanism *p* and *q*.

respectively. The inking mechanisms *r* and *s* are positioned above their plate cylinders which arrangement, as is known, greatly improves the effect of color distribution.

6 Both the plate cylinders *g* and *l* may be moved out of their operative position together with the small impression cylinder *c* by means of the control arrangement *t* which comprises a common control rod *u* adapted 10 to act upon the eccentric bearings *v*, *w*, *x* for the said cylinders. For this purpose the two eccentric bearings *v* and *w*, which serve for the displacement of the plate cylinders *g* and *l* are disposed at different sides of the 15 plane passing through the axes of the two plate cylinders and the blanket cylinder. The delivery cylinder *n* is arranged so as to be able to collect two sheets.

The machine according to the invention 20 may also be used for "perfecting" which, in the printer's terminology, means to print a sheet upon both sides. In this case the small impression cylinder *c* must be provided with an india rubber blanket upon which to receive the printing from the printing surface *d* during its first rotation. During the second rotation it seizes a sheet, which is supplied from the feed table, by means of its grippers *b* and transmits same to the grippers *h* of the blanket cylinder. The sheet 25 then comes into contact with the india rubber blanket *i* and is printed upon on both sides while passing between the impression cylinder *c* and the blanket cylinder, whereupon it is moved to the delivery roll *n*.

In the embodiment of the printing machine shown in the drawing there is shown a standard *y* upon which a pair of adjustable cutting cylinders *z* is mounted, between which a continuous web of paper *b'* may 40 be supplied from a roll of paper *a'*. The sheets cut from the said web are seized by the grippers *b* of the impression cylinder *c* and moved through the printing machine in the afore described manner; for which 45 purpose the grippers *b* of the impression cylinder may be made adjustable.

This application is a division of the application of Alfred Fallot, Serial No. 690,030, 50 filed February 1, 1924, now Patent No. 1,668,999, May 8, 1928. The single figure in this application corresponds to Fig. 1 as originally filed in said application.

Having now particularly described the 55 nature of my said invention and in what manner the same is to be performed; I declare that what I claim is:—

1. In a two color rotary printing machine a blanket-cylinder, two blankets on the 60 same, two plate cylinders adapted to cooperate with said blanket cylinder, an impression cylinder of only the half diameter of the blanket cylinder, a paper feeding device, a set of grippers on the said impression cylinder by means of which the sheet coming

from the feeding device is passed once around the impression cylinder to be printed upon by one of the blankets of the blanket cylinder, a second set of grippers on the blanket cylinder by means of which the 70 sheet thereupon is caught and is printed upon by passing between the impression cylinder and the second blanket of the blanket cylinder and a delivery device for removing the printed sheet from the machine. 75

2. In a two color rotary printing machine, a blanket cylinder, two blankets on the same, a plate cylinder on each side of the blanket cylinder, the axes of the blanket cylinder and of the two plate cylinders all lying 80 in one plane, offset surfaces on the plate cylinders arranged in such a manner, that the pressure of both plate cylinders upon the blanket cylinder commences simultaneously, an impression cylinder of only the half 85 diameter of the blanket cylinder, a paper feeding device, a set of grippers on the said impression cylinder by means of which the sheet coming from the feeding device is passed once around the impression cylinder 90 to be printed upon by one of the blankets of the blanket cylinder, a second set of grippers on the blanket cylinder by means of which the sheet thereupon is caught and is printed upon by passing between the impression cylinder 95 and the second blanket of the blanket cylinder and a delivery device for removing the printed sheet from the machine.

3. In a two color rotary printing machine, a blanket cylinder, two blankets on the same, a plate cylinder arranged on each side of the blanket cylinder and adapted to cooperate with the same, the axes of the blanket cylinder and of the two plate cylinders all lying in one plane, eccentric bearings for said plate cylinders, the centres of such eccentric bearings being disposed at different sides of the common plane passing through the axes of the two plate cylinder and the blanket cylinder, an impression cylinder of only the half diameter of the blanket cylinder, an eccentric bearing for said impression cylinder, common means for simultaneously moving all eccentric bearings in order to bring said plate cylinders and said impression cylinder out of operative engagement with the blanket cylinder, a paper feeding device, a set of grippers on the said impression cylinder by means of which the sheet coming from the feeding device is passed once around the impression cylinder to be printed upon by one of the blankets of the blanket cylinder, a second set of grippers on the blanket cylinder by means of which the sheet thereupon is caught and is printed upon by passing between the impression cylinder and the second blanket of the blanket cylinder and a 100 delivery device for removing the printed sheet from the machine. 105

delivery device for removing the printed sheet from the machine.

4. In a two color rotary printing machine, a blanket cylinder, two blankets on the same, two plate cylinders adapted to cooperate with said blanket cylinder, an impression cylinder of only the half diameter of the blanket cylinder, a paper feed table, a set of grippers on the said impression cylinder by means of which the sheet
- 10 coming from the paper feed table is passed once around the impression cylinder to be printed upon by one of the blankets of the blanket cylinder, a second set of grippers on the blanket cylinder by means of which the sheet thereupon is caught and is printed upon by passing between the impression cylinder and the second blanket of the blanket cylinder and a delivery device for removing the printed sheet from the machine.
